Inventor
James Teachout

United States Patent Office.

JAMES TEACHOUT, OF WATERFORD, NEW YORK.

Letters Patent No. 72,115, dated December 10, 1867.

IMPROVEMENT IN ROTARY TAKE-UP FOR KNITTING-MACHINES.

The Schedule referred to in these Letters Patent and making part of the same.

TO ALL WHOM IT MAY CONCERN:

Be it known that I, JAMES TEACHOUT, of Waterford, in the county of Saratoga, and in the State of New York, have invented a new and useful Improvement in Knitting-Machines, on that part known as "take-up," or the take-up motion; and I do hereby declare that the following is a full, clear, and exact description of the construction and operation of the same, reference being had to the annexed drawings, making a part of this specification, in which—

Figure 1 is a vertical elevation of my invention.

Figure 2 is an inverted sectional view of the same, taken in the line xx , fig. 1.

Figure 3 is a detail of my invention, exhibiting a top view thereof.

The object of my invention is to so construct and arrange certain necessary parts of take-ups of knitting-machines, together with the actuating devices employed therewith, to insure a uniform tension to the "goods" or knit-cloth while being wound from the needle-cylinders, and also to simplify the construction of the same, and to render them less liable to derangement, and more easily rotated, than apparatus heretofore used for the purpose.

A, figs. 1 and 2, represents the cross-beam which supports and forms a bearing for the "take-up" B. A scroll-plate, C, is secured to the cross-beam A, and engaged with the oblique-toothed wheel D, on whose shaft is secured also a bevel gear, e, which in turn meshes into a corresponding gear, f, which is secured, with the reverse-gear g, to a hollow shaft, or bushing, which turns loosely on the shaft h. A concave gear-wheel, i, is secured to the shaft h by means of a pin or key. The wheels D e f g turn in a bearing-piece, K, which has a horizontal motion, and is guided by the stem or shank l and shaft h. An L-shaped lever, m, is pivoted to the take-up frame B. A slot, n, is formed in it, as shown, into which a pin, o, which is secured to the bearing-piece K, is inserted loosely. A spiral or other spring, p, is attached, as shown, to the outer extremity of the lever m, which presses the gear or clutch g in contact with a corresponding one, i, secured to the shaft h. The shaft h turns in bearings secured to the frame B. Said shaft is provided with a bevel gear, q, which is made to mesh into a similar or corresponding one, q', also secured to the nearly-vertical shaft r. This shaft also has its bearings secured to the frame B, and is provided with a narrow-bevel gear, s, which can be adjusted on the shaft r in such a manner as to engage or mesh into either of two, three, or more concentric-bevel gears, s', secured to the shaft of the take-up roll t. A ratchet-wheel, u, is also secured to said shaft, t. The operation of the ratchet-wheel and pawls are well known, and therefore need no explanation in this specification. The scroll-plate C may have one, two, or more cams or curved guides, v, as may be thought most desirable for the work to be done. The design of providing the wheel s' with two or more concentric-toothed rings is to vary the speed of the take-up rolls t t'.

It will be seen, when the take-up is made to revolve, and the oblique-toothed wheel D turns inward tangentially toward the scroll-plate C, and the shafts h r and t t' are made to revolve until the cloth overcomes the resistance of the spring p on the lever m, when the scroll C draws the gear D and its appendages inward, and disengages the clutch g from the clutch i, secured to the shaft h.

What I claim as my invention, and desire to secure by Letters Patent, is—

1. I claim the stationary scroll-plate C, placed over the centre of motion of take-up of knitting-machines, for the purpose described.
2. I claim, in combination with the scroll-plate C, the toothed gear D, for the purpose herein set forth.
3. I claim the toothed wheel D or its equivalent, either separately, or combined with the described appendages, e, f, g, i, K, arranged as shown and described, and operating substantially in the manner and for the purpose specified.
4. I claim, in a combination with the above, the adjustable gear s and concentric gears s', for the purpose described.

Having thus described my invention, I will hereunto subscribe my name, in the presence of two witnesses.

JAMES TEACHOUT.
